[57] **CLAIM**

The ornamental design for a lavatory, as shown and described.

DESCRIPTION

FIG. 1 is a right, top, front perspective view of a lavatory embodying my new design;

FIG. 2 is a top plan view thereof;

FIG. 3 is a front elevational view thereof;

FIG. 4 is a right side elevational view thereof, the left side elevational view being a mirror image of the right side shown;

FIG. 5 is a rear elevational view thereof;

FIG. 6 is a bottom plan view thereof;

FIG. 7 is a cross-sectional view taken along line 7—7 of FIG. 2; and,

FIG. 8 is a cross-sectional view taken along line 8—8 of FIG. 2.

The broken line representations of a mounting environment in FIG. 1 and of holes in FIGS. 1, 2, 3, 5, 6, and 7 are for the purpose of illustration only, and form no part of the claimed design.
